UNITED STATES PATENT OFFICE.

HENRY W. PETERS, OF BOSTON, MASSACHUSETTS.

FINGER RING.

Application filed August 28, 1924. Serial No. 734,707.

To all whom it may concern:

Be it known that I, HENRY W. PETERS, a citizen of the United States, residing at Boston, in the county of Suffolk and State of Massachusetts, have invented a new and useful Finger Ring, of which the following is a specification.

This invention relates to finger rings and other articles of jewelry and more particularly to a means whereby an onyx, plain or encrusted, or other stone can be set without requiring the services of an expert. Heretofore in the setting of onyx rings it has been the practice where monograms or other emblems or the like are mounted on the onyx, to drill through the stone and subsequently insert thereinto a peg or stud projecting from the monogram or other ornamentation to be placed on the onyx. The free end of this peg or stud is upset to hold the parts assembled. In the operation of assembling the metal with the stone considerable skill is required and even under the most favorable circumstances the operation often results in the splitting of the stone and consequent loss of time and material.

As before stated, the present invention has for an object a special means for holding a stone assembled with a ring, pin or the like whereby it has the appearance of the so-called mounted onyx or encrusted stone but does not require the skill usually called for in assembling the parts.

Another object is to so mount the stone that it will be fully protected and the danger of cracking or chipping in the ordinary process of manufacture and wear is practically eliminated.

Another object is to provide a means of mounting a stone whereby there is effected a great saving of labor and consequent reduction in cost of manufacture.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention as has been shown.

In the accompanying drawings the preferred forms of the invention have been shown.

In said drawings

Figure 1 is a perspective view showing a portion of a ring and a specially prepared box prior to being assembled with a stone or the like.

Fig. 2 is an elevation of a portion of a ring, the box being shown assembled therewith ready to receive the stone or the like, said box being in section.

Fig. 3 is a plan view of the box assembled with the stone, a portion of the ring being illustrated.

Fig. 4 is a view similar to Fig. 1 showing the first stage in the production of a slightly modified form of ring.

Fig. 5 is a view showing the box and ring assembled ready to receive a stone or the like, the box being in section. Fig. 6 is an elevation of a portion of a ring showing the box thereon in section assembled with the stone.

Fig. 7 is a perspective view of a modified form of ring, a portion being broken away, said ring being ready to receive a stone or the like.

Fig. 8 is a section through the structure shown in Fig. 7.

Fig. 9 is a similar view showing a stone assembled with the ring.

Fig. 10 is a perspective view of another form of box.

Fig. 11 is a section through the box, the same being shown assembled with a ring and ready to receive a stone.

Fig. 12 is a plan view of the structure shown in Figs. 10 and 11, a stone being assembled therewith.

Fig. 13 is a perspective view of another form of box.

Figure 14 is a view thereof assembled with a portion of a ring, the box being in section and ready to receive a stone or the like.

Referring to the figures by characters of reference 1 designates the band portion of the ring provided with a plate or base 2 on which the mounted onyx, enamel, or other material is to be placed. In the structure shown in Figs. 1, 2, and 3 a box 3 is employed, this having downwardly extending flanges 4 along three sides which are adapted to be soldered to three of the side edges of the plate. The top of the box is cut out as at 5 before it is soldered on to provide any suitable designs such as an emblem, monogram or the like. Or, if preferred an emblem

or the like of the same or a different metal, can be soldered or otherwise attached to the top of the box before it is applied to the plate. Another flange 6 is extended laterally from the open side of the box in alignment with the cut out face thereof so that when the box is joined to the plate 1 the flange will be extended as shown in Fig. 2. The onyx, enamel or other material to be mounted and which is so shaped as to fit snugly within the box, is adapted to be inserted edgewise under the flange 6 so as to completely fill the box, as shown at 7, after which flange 6 is bent downwardly against the insert so as to come against and be soldered to the plate 2, if so desired. Obviously a ring mounted in this manner has the appearance of the ordinary mounted ring but the parts can be assembled more readily, the operation does not require the services of a skilled jeweler, and the mounted stone, enamel or the like will be fully protected against chipping or breaking while being worn.

Obviously other means than those already described and illustrated can be used for holding the mounting on the ring. For example, and as shown in Fig. 4, instead of providing the box 8 with a laterally extending flange, a series of teeth or prongs 9 can be projected laterally from the open face 10 of the box and from the side flanges. Similar prongs or projections 11 can also be extended laterally from the plate or base 12. Thus after the stone 13 or other insert has been placed in the box, the prongs or teeth can be bent against the exposed side of the insert as in Fig. 6 and will serve to hold the same firmly in position.

In Fig. 7 another way of mounting the insert has been illustrated. In this form of ring the box 14 is made integral with the band 15 and is provided with a cut-out face 16. The box opens downwardly through the band and the walls of the box are provided with projecting teeth 17 which, after the insertion of the stone 18 or the like can be bent against the inner face of the stone as shown particularly in Fig. 9. It is to be understood of course that the cut-out face 16 can either be cast integral with the box or can be formed of a separate plate soldered onto the box.

In Figs. 10, 11 and 12 another construction has been illustrated. This form of device includes a box 19 having a cut-out face 20 and instead of providing the open side of the box with a single flange as indicated at 6 in Fig. 1, tongues 21 can be formed by extending the side flanges 22 of the box laterally beyond the face 20. This box is adapted to be soldered or otherwise joined to the plate or base 23 after which the stone or other insert is placed in the box, and the tongues

21 bent inwardly. Thus the insert, illustrated at 24, will be held firmly in place.

In Fig. 13 the box is of a skeleton form and includes a cut-out plate 25 from the edges of which are extended attaching lugs 26. These lugs are arranged along three sides of the plate and at right angles thereto and are adapted to be soldered or otherwise connected to the plate 27 of the ring. This is shown in Fig. 14. Additional lugs 28 are extended from the remaining edge of the plate 25 and are flush with the plate. Thus a stone or other insert can be placed in the box after which the lugs 28 can be bent downwardly and, if desired, soldered to the plate 27.

In Figs. 15 and 16 the ring is shown provided with a box 29 having an open side which can be closed by means of a hinged leaf 30. Thus after the stone or the like has been inserted in the box the leaf can be swung to shut position and fastened in any suitable manner, as by means of a snap 31.

It is to be understood of course that the modifications illustrated are only a few of the various means that might be devised for holding a stone, enamel or other article properly mounted. Although enamel and stones have been referred to as the articles to be combined with the ring it will be obvious that other materials can be used and in view of this fact it is particularly advantageous to combine with the mounted stone a box containing the design to be displayed. By constructing a ring in the manner disclosed it becomes unnecessary to use rivets or solder for mounting the design on the stone or the like and, obviously, the inserts can be changed whenever desired so as to meet the taste of the user.

What is claimed is:—

1. An article of jewelry including a base, a holding device integral therewith having an open face, there being also a second open face, and a member insertable through said second open face into the holding device for exposure through the first mentioned open face, and means for retaining the inserted member against removal through said second open face.

2. An article of jewelry including a base, a holding device integral therewith having an open face and a second face, a separate member, said second face having means for the insertion of said member for exposure through the first named face, said first named face having means for preventing removal of said member therethrough, and means movable to position across said second face for retaining the member against withdrawal.

In testimony that I claim the foregoing as my own, I have hereto affixed my signature,

HENRY W. PETERS,
